UNITED STATES PATENT OFFICE.

FRANK SCHAFER, OF PHILADELPHIA, PENNSYLVANIA.

MACHINE FOR MAKING TUBES.

No. 857,678.

Specification of Letters Patent.

Patented June 25, 1907.

Application filed February 11, 1902. Serial No. 93,522.

To all whom it may concern:

Be it known that I, FRANK SCHAFER, of the city and county of Philadelphia, State of Pennsylvania, have invented a new and useful Improvement in Machines for Making Tubes, of which the following is a specification.

My invention consists of an improved machine for making tubes, the object being to provide in a single structure devices for forming a tube having angular sides, for gluing the same, for applying frictional matter to one of the sides thereof, for printing upon a side of the tube, and lastly for cutting the tube into lengths so as to serve as the tube for match boxes.

It further consists of novel details of construction, all as will be hereinafter fully set forth and particularly pointed out in the claims.

Figure 1 represents a side elevation of the front end portion of a machine constructed in accordance with my invention. Fig. 2 represents a side elevation of the rear end portion thereof, said figures being separated for convenience of construction. Fig. 3 represents a top plan view of the portion of the machine shown in Fig. 1. Fig. 4 represents a top plan view of the portion of the machine shown in Fig. 2. Figs. 5, 6, 7, 8, 9, 10, 11, 12, 13, 14, 15, 16, 17, 18, 18^x, 19, and 20 represent vertical sectional views, taken respectively on the lines 5—5 to 20—20, both inclusive, of Figs. 1, 2, 3 and 4. Fig. 21 represents an end elevation at the rear end of the machine, showing the cutting devices in detail. Fig. 22 represents a horizontal section taken on the line 22—22 of Fig. 21. Fig. 23 represents a plan of the wheel for applying the glue by which the sand or other friction material is caused to adhere to the box. Fig. 24 represents a section thereof. Fig. 25 represents a perspective view of the finished tube after being cut into sections, the printed matter being omitted. Fig. 26 represents a modification of the ink feeding devices for printing rollers. Fig. 27 is an edge view on an enlarged scale of the wheel for applying glue shown in Fig. 23. Fig. 28 represents a side elevation of a portion of said wheel in the act of applying the glue.

Similar numerals of reference indicate corresponding parts in the figures.

Referring to the drawings: 1 designates a table for the front end portion of the machine and 2 the table for the rear end portion

of the machine, upon which the operative parts thereof are mounted, said tables being conveniently secured together by means of the strips 3. As the supports and bearings 60 for the different rollers and other devices which act upon the tube as it passes through the machine in the course of formation are of well-known construction and clearly shown in the drawings, I will for the sake of brevity not refer specifically thereto, but only to the parts supported thereon. The roller 4 carrying the roll of cardboard, strawboard or other material of which the tube is to be formed is mounted at the front end of the 65 machine and the strip 5 taken therefrom is passed through the different rollers and other devices to the other end of the machine where it passes between the feed rollers 6 suitably driven, which draws the material 70 through the machine in the course of the formation of the tube. After leaving the roller 4 the material first passes between the grooved roller 7 and the scoring disks 8 (Fig. 5), the shaft of the latter being driven by the 75 gearing hereinafter described. These disks 8 score and bend the strip on the lines 9 shown in Fig. 3. Then the scored and bent strip passes between the rollers (Fig. 6) 10 and 11, the roller 11 being situated over a 80 longitudinal former 12, the front end of which is located between said rollers 10 and 11 and the scoring devices. The rollers 10 are situated at an incline on opposite sides of the former and thus bend the strip to the position shown in Fig. 6 to guide it to the next set of rollers (Fig. 7), consisting of vertical side rollers 13 and horizontal upper roller 14 which guide the strip to the next set of rollers with the long sides thereof parallel and hugging the sides of the former, while the lower edges of the strip project below the lower edge of the former, it being noted that on one side the strip projects below the lower edge of the former a little greater distance than on the other. The short side of the strip is then to be turned in to form the inner flap of the connecting flaps of the tube.

In Fig. 8 is shown the first step in bending in the inner flap. In this figure the vertical side 10 rollers 15 and upper horizontal roller 16 are employed while below the former is an inclined roller 17 which bends the inner flap to the position shown in said Fig. 8, while in Fig. 9 the position of the roller 18 that engages the inner flap is changed to horizontal and in connection with the vertical side rollers 19 and

upper horizontal roller 20 the tube is held in position shown in said Fig. 9.

The next operation is the application of adhesive material to the outer surface of the 5 inner flap. This is applied by a disk 21 driven by mechanism hereinafter described and which is mounted in the receptacle 22 containing the adhesive material. This disk contacts with the said inner flap (Fig. 10), 10 while the outer flap is held out of contact with the disk 21 by means of a guide 23 (Fig. 11). After the glue is thus applied the next step is shown in Fig. 12 which is the preliminary bending of the outer flap and upon the 15 inner flap, the vertical rollers 24 and horizontal roller 25 holding the tube upon the former while the inclined roller 26 situated beneath the former bends the outer flap partially upon the inner. In Fig. 13 is shown the last 20 operation upon the tube before it leaves the former. In this figure are the vertical rollers 27 on the sides of the former and the horizontal rollers 28 above and below the same, the lower horizontal roller pressing the adjacent 25 faces of the flaps firmly together and cause them to adhere. After leaving the former the tube is first flattened out by being passed through the vertical rollers 29 shown in Fig. 14. In flattening out the tube it will 30 be seen that the glued flaps are at the lower edge thereof and on the left hand side in the direction of its movement.

The next operation is the application of the sand or other material, it being noted 35 that as the long continuous tube is finally cut into short sections 30, shown in Fig. 25, it is desirable to apply the sand to a section only thereof as shown at 31. To accomplish this I employ a wheel having a segmental 40 periphery so as to touch the outer flap of the tube at intervals. I also serrate or notch the periphery of this roller 32 so as to more effectively apply the glue and to prevent the glue from being pressed beyond the sides of 45 the roller as the glue is applied. By notching or serrating the periphery of the roll 32 so that its periphery is provided with a series of intersecting grooves or channels, I am, as above pointed out, enabled to more effectively 50 apply the glue. If this disk had a smooth periphery the glue would adhere to the surface thereof and would be pressed beyond the sides of the disk, and thus only a small portion applied where most needed, 55 but when each of these little indentations in the periphery of the disk carries a supply of glue the same will be left upon the tube after the disk rolls cross the same. An end elevation of the glue applying devices is shown in 60 Fig. 15, wherein the tube is supported on one side by a vertical roller 33, while the glue roller 32 on a vertical axis is situated opposite the outer flap. Mounted on the glue receptacle 34 is a shaft 35 driven by mechanism 65 hereinafter described and carrying a disk 36

submerged in the glue and contacting with a disk 37 mounted on an inclined axis and which contacts with the glue feeding roller 32. The shaft carrying the inclined roller 37 is provided with the gears 38 and 39, the latter meshing with the gear 40 on the shaft 35 and the former with the gear 41 rigid with the roller 32, whereby the disk 37 and roller 32 are driven.

The next step is to apply sand or other friction material to the glued surfaces of the outer flap and the mechanism for accomplishing this is shown in elevation and partly in section in Fig. 17, it being noted that a support and guide 42 is situated in the rear 7 of the glue applying mechanism to hold the traveling tube in the correct position, and it will be noted that supports of the nature shown in Fig. 16 can be placed at convenient points throughout the machine as found desirable. Situated to one side and above the path of the tube is a sand hopper 43 having a spout 44 at its lower end adapted to deliver the sand against the lower flap of the tube, a receptacle 45 being placed below the same in which the surplus sand accumulates. I prefer to employ an agitator to insure a continuous flow of sand and this may consist of a rod 46 having a flattened end terminating near the upper end of the spout 44 and being 8 geared to a shaft carrying a gear wheel 47 that is suitably driven as hereinafter described.

The next step is the drying of the glue by which the sand is held and to accomplish this, as shown in Fig. 18, I employ an air blast, the fan 48 delivering to a nozzle 49 extending longitudinally along the sanded flap, whereby the current of air is blown against and dries the same. It is however found that small particles of the sand will not adhere sufficiently, and I have arranged air blasts, shown in Fig. 18^x, just in the rear of the nozzle 49, said air blast being formed by tubes 50 receiving their supply of air from the fan 48 and projecting a forcible current of air against the sand to blow away any of these small particles. Then the tube passes between the vertical guide rollers 51 before passing to the printing mechanism, it being noted that the guide rollers 51 on the side of the tube carrying the sand is shorter so as not to contact therewith. The printing rollers 52 (Fig. 20) are mounted on opposite sides of the tube and carried by vertical shafts 53 and are situated between the feed rollers 6, being the last set of rollers, and a set of feed rollers 54 situated also on opposite sides of the tube. The rollers 6, 52 and 54 are mounted on vertical shafts suitably geared to each other and with the main driving shaft 55 by the gearing shown, and ink is fed to the rollers 52 by the small rollers 56, the shafts of which are geared to the printing rollers. The ink is applied to the inking rollers 56 by means of

the inclined inking rollers 57 that contact also with the rollers 58 situated within the inking receptacles 59. The shafts of these rollers 58 are geared to a cross shaft 60, which by means of a shaft 61 is geared to the main driving shaft 55 as shown in Fig. 4. It is from this shaft 60 that the driving parts herefore described are also driven, conveniently in the following manner: A chain or belt 62 is trained around a gear on the shaft 60 and around the gear 63 on the shaft 35 of the gluing mechanism shown in Fig. 15. A chain or belt 64 is trained around another gear upon the shaft 60 and around the gear 47 of the sanding mechanism shown in Fig. 17. A chain or belt 65 is trained around another gear of the shaft 60 and around a gear 66 on the shaft 67 carrying the gluing disk 21, while a chain or belt 68 is trained around another gear 69 on the shaft 67 around a gear on the shaft 70 carrying the scoring disks 8.

The last and final operation upon the tube is the cutting of the same into sections as shown in Fig. 25. This is accomplished by a reciprocating knife 71 (Figs. 21 and 22) carried by a slide 72 mounted in guides 73 on the upright end plate 74 of the machine. The edge of the knife 71 passes over the edge of the cutting plate 75, conveniently countersunk into the end plate 74 at the far side of the guide opening 76 through which the tube is fed. As the tube is fed continuously the gearing for reciprocating the knife 71 is so arranged that it makes a quick advance and return during the cutting operation, so as not to impede the progress of the tube, the same being secured by means of the gears 77 and 78 mounted eccentrically upon the shafts 79 and 80. The shaft 79 carries a crank disk 81 that is connected with the slide 72 by the pitman 82. The shaft 80 is geared to the main driving shaft 55 by a chain or belt 83.

It is understood that although I have shown a former rectangular in cross section, yet other shapes may be employed to form tubes of other cross sectional figures.

It is not absolutely necessary in the organization of the machine that the glue for binding the flaps, or for causing the frictional material to adhere should be applied at the various stages of the formation of the tube illustrated, as it is obvious that it could be applied at other stages without departing from the spirit of my invention, and further that various other changes could be made in the construction and arrangement of the parts so long as the equivalent of those shown are employed.

Having thus described my invention, what I claim as new, and desire to secure by Letters Patent, is:—

1. In a tube making machine, means for supplying a continuous strip of material, devices for scoring said strip of material longitudinally, means for bending said scored

strip along the said scores to form flaps, means for applying adhesive material to the outer face of one of the edge flaps, means independent of the bending means for holding the outer flap from contact with the adhesive-applying means, means for pressing the other edge flap upon the outer face of the flap to which the adhesive material has been applied for forming a tube, means for flattening out the said tube after the overlapping portions have been caused to adhere, means for applying the adhesive material to the exterior of the tube, means for applying frictional material to said adhesive material, and means for cutting said tube into sections after the tube has been subjected to the operations of the above mentioned instrumentalities.

2. In a tube making machine, a rigid longitudinal former, means for scoring and feeding a strip of material thereto, oppositely inclined means for giving the initial bend to the strip, means embodying an independent roller for each side for bending the strip around all of the sides of the former, an adhesive-applying device, means independent of the bending means for holding the outer flap out of contact with the adhesive-applying device, means including an inclined roller for bending the outer flap and pressing the adjacent faces of the flaps firmly together.

3. In a tube making machine, a rigid longitudinal former, means for feeding a strip thereto and means for bending the strip around all the sides of the former, means for applying adhesive material to the outer face of one of the edge flaps of the strip, means independent of the bending means for holding the outer flap away from the adhesive-applying means as the latter applies the adhesive material to the inner flap and means for pressing the other edge flap upon said flap to which the adhesive material has been applied.

4. In a tube making machine, means for feeding a strip, a grooved roll over which the strip passes, rotatable scoring disks situated opposite the grooves of said roll and between which and said rolls the strip passes, a rigid longitudinal former extending from said roller to the point where the tube is completed, inclined rollers arranged upon opposite sides of said former to give the initial bend to the strip, an adhesive-applying device independent rollers arranged upon each side of said former and disposed at intervals throughout its length to bend the strip around all sides of said former and to press its overlapped edges together and means independent of the bending means for holding the outer flap out of contact with said adhesive applying device.

5. In a tube making machine, means for feeding a strip, a grooved roll over which the strip passes, rotatable scoring disks situated opposite the grooves of said roll and between

- which and said rolls the strip passes, a rigid longitudinal former extending from said roller to the point where the tube is completed, inclined rollers arranged upon opposite sides of said former to give the initial bend to the strip, an adhesive-applying device independent rollers arranged upon each side of said former and disposed at intervals throughout its length to bend the strip around all sides of said former and to press its overlapped edges together, one of the rollers for bending the outer flap of said strip being inclined and means independent of the bending means for holding the outer flap out of contact with said adhesive applying device.
6. In a tube making machine, a feeding device, a scoring device, a rigid former, rollers mounted on inclined shafts for partially bending said strips around said former, rollers disposed at points along and situated over said former, rollers situated on opposite sides of said former and parallel with the sides thereof, means for bending the said strip around all sides of the former, adhesive-applying means and means independent of said rollers and co-operating therewith for holding the outer flap away from the adhesive-applying means while the adhesive material is being applied to the other flap for securing the overlapping portions of the same together.
7. In a tube making machine, a feeding device, a scoring device, a rigid former, means for partially bending a strip around said former, and means independent thereof for bending one of the overlapping portions of the strip against the bottom of said former and consisting of a roller situated over said former, rollers situated on opposite sides thereof and practically parallel therewith, and a roller situated below the former and practically parallel with the bottom surface thereof, and means for overlapping the edges of said strip upon said former and securing the same together and all arranged to act in successive order.
8. In a tube making machine, a rigid former, means independent of each other disposed upon the various sides of the former for bending a strip around all sides of the former while the strip is resting against said former, means for applying adhesive material to the outer face of one edge portion of the strip, an inclined roller for subsequently bending the outer edge of said strip, and means for compressing the last-named edge portion of the strip upon the edge to which the adhesive material has been applied.
9. In a tube making machine, a rigid former, means for bending a strip around the same, a rotatable disk adapted to engage one edge portion of said strip, means for applying adhesive material to said disk, means independent of and co-operating with said disk to hold the opposite edge portion of the strip from contact with said disk, and means for bending the other edge portion of the strip upon the edge portion of the strip to which the adhesive material has been applied while the same is held against said former.
10. In a tube making machine, a rigid former, and means for bending a strip around all sides of the same, means for applying adhesive material to one edge portion of the strip, and a guide independent of the bending means for engaging the other edge portion of the strip situated adjacent said devices for applying adhesive material and adapted to hold said other edge portion of the strip away from the pasting device.
11. In a tube making machine, a rigid former, independent means upon the various sides of the former for partially bending a strip around all sides of the same, means for applying adhesive material to one edge portion of said strip, means for holding the opposite edge portion of the strip away from the pasting device, and means for partially bending the other edge portion toward the same consisting of guide rollers situated on a plurality of sides of the former, and an inclined roller adapted to bend the other overlapping portion partially toward the edge portion to which the adhesive material has been applied.
12. In a tube making machine, a rigid former, independent means upon the various sides of the former for bending a strip around all sides of the same, means for overlapping the edges, means for applying adhesive material to one of the overlapping edge portions thereof, means for holding the opposite edge portion of the strip away from the pasting device, and means for compressing said overlapping portions, consisting of rollers situated on all sides of the former and contacting with the strip.
13. In a tube making machine, a rigid former, extending the whole length upon which the completed tube is formed, independent means upon the various sides of the former for bending a strip around all sides of the same an inclined roller for giving the initial bend to the outer flap adhesive applying means, means for holding the outer flap away from the adhesive applying means while the adhesive material is being applied to the other flap, means for subsequently securing the overlapping edge portions thereof together, and rollers situated on opposite sides of the path of the tube and practically parallel and between which the tube passes, the distance between said rollers being such that said tube is flattened.
14. In a tube making machine, devices disposed independently upon the various sides of the tube for forming a tube, a rigid former extending to the point where the completed tube is formed, means for applying

adhesive material to the surface of a portion only of said completed tube, means for applying frictional material to said adhesive material, and means for severing said tube 5 into sections after the frictional material has been applied, and after the tube has been subjected to the operation of the above mentioned instrumentalities.

15. In a tube making machine, means disposed independently upon the various sides of the tube for forming a tube, a rigid former extending to the point where the completed tube is formed, means for applying adhesive material at intervals to an outer surface of 15 the tube, means for applying frictional material to said adhesive material, means for drying said adhesive and frictional materials and means for severing said tube into sections after the frictional material has been applied 20 and at points situated between the portions to which the adhesive material is applied.

16. In a tube making machine, means disposed independently upon the various sides

of the tube for forming a tube, a rigid former extending to the point where the completed 25 tube is formed, means for applying adhesive material thereto, and for supplying frictional material to said adhesive material, and means for directing a current of air against the portion of the tube to which the frictional 30 material is applied after said frictional material has been applied whereby the surplus is removed.

17. In a tube making machine, means disposed independently upon the various sides 35 of the tube for forming a tube, a rigid former extending to the point where the completed tube is formed, means for applying frictional material to a surface thereof, and means for directing an air blast against the said frictional material after it is applied to the tube 40 whereby the surplus is removed.
